[57] CLAIM

The ornamental design for an invertible casserole-roaster or the like, substantially as shown and described.

DESCRIPTION

FIG. 1 is a top front perspective view of an invertible casserole-roaster or the like showing my new design in the position of a casserole;

FIG. 2 is a top plan view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a bottom plan view thereof; and
FIG. 8 is a front perspective view thereof in the inverted position of a roaster.
